UNITED STATES PATENT OFFICE.

EDGAR E. BROSIUS, OF PITTSBURGH, PENNSYLVANIA.

BLAST-FURNACE TAPPING APPARATUS.

Application filed January 3, 1921. Serial No. 434,522.

To all whom it may concern:

Be it known that I, EDGAR E. BROSIUS, a citizen of the United States, residing at Pittsburgh, in the county of Allegheny and State of Pennsylvania, have invented certain new and useful Improvements in Blast-Furnace Tapping Apparatus, of which the following is a full, clear, and exact description, reference being had to the accompanying drawings, forming part of this specification, in which—

Figure 1 is a sectional elevation showing one form of apparatus embodying my invention, certain of the parts being shown in dotted lines and some of the parts being shown in another position in dotted lines.

Figure 2 is a side elevation showing the means for suspending the apparatus when not in use.

Figure 3 is a longitudinal central section of one form of drill embodying my invention, with portions thereof broken away.

Figure 4 is a plan view, partly broken away, of a drill point.

Figures 5 and 6 are end views of the same, taken from opposite ends.

Figure 7 is an enlarged sectional view of a portion of the apparatus shown in Figure 3.

Figure 8 is a section on the line VIII—VIII of Figure 7.

My invention has relation to blast furnace tapping apparatus, and is designed to provide a simple and effective form of apparatus for use in drilling out the tapping holes of blast furnaces. The invention is further designed to provide apparatus of this character which can be readily moved into and out of operative position; and which, when not in use, occupies a position in which it is out of the way of other operations about the furnace.

The nature of my invention will be best understood by reference to the accompanying drawings, in which I have shown a preferred embodiment thereof, and which will now be described, it being premised, however, that various changes can be made in the construction, arrangement and combination of the several parts without departing from the spirit and scope of my invention as defined in the appended claims.

In these drawings, the numeral 2 designates a portion of a blast furnace wall; 3

one of the mantle supporting columns; and 4 the bustle pipe. 5 designates the usual splash plate above the tapping out opening 6; and 7 designates one of the mud-gun dogs used in holding the mud-gun in operative relation to the tapping hole in plugging the latter. These parts are all of the usual character and need not be described in detail.

In accordance with my invention I provide a suitable drill which is preferably of the construction shown in Figures 3 to 7, inclusive. This drill comprises an outer casing 8, one section of which constitutes a power cylinder 9 having a valve chest 10, in which is mounted an admission valve 11 for controlling the supply of fluid to opposite ends of the cylinder through the ports 12. 13 designates a piston arranged to reciprocate in the cylinder 9, and which is rigidly secured to an elongated hollow sleeve 14 which is arranged to reciprocate with the piston 13. At its forward end the sleeve 14 is rigidly secured to a nut member 15 having an internal thread, or projections, 16, which are adapted to the grooves 17 of a spirally grooved rod 18 located within the sleeve 14. At its forward end the rod 18 carries a drill socket 19 adapted to receive the drilling tool 20. 21 designates a series of clutch balls which are seated in openings 22 in a spacer sleeve 22 and which seat at their inner sides against a split sleeve 23 surrounding the front end portion of the rod 18. Externally these balls seat within a sleeve 24 having an internally tapered portion 25 at its rear end.

The valve 11 is automatically actuated by any suitable means, such as the two-armed lever 26, one arm of which is connected to the valve stem 27 and the other arm of which is connected to a tappet rod 28. This tappet rod extends through the nut member 15 and terminates at its forward end in the head 29. The rod 18 is preferably provided with a longitudinal passage 30 extending longitudinally therethrough, the front end of this passage being arranged to communicate with the interior of the hollow drilling tool 20, and its rear end being in communication through a port 31 in the cap 32, with a pipe 33 having a flexible portion 36 which is connected with the exhaust 37 of the valve chest 10.

The operation of the drill will be readily understood. Actuating fluid being admitted to the rear end of the cylinder 9, the piston 13 is moved forwardly, carrying with it the sleeve 14. This, through the nut 15, rotates the rod 18 and drilling tool 20, and at the same time advances said tool to the work. When the piston reaches the limit of its forward stroke, the nut 15 engages with the head 29 of the tappet rod 28, thereby actuating the lever 26 to reverse the valve 11. Upon the back stroke of the piston, the sleeve 14 and nut 15 are retracted to an extent equal to the full travel of the piston 13; but the rod 18 and the drilling tool 20 have only a limited retraction owing to the fact that as soon as the clutch balls 21 engage with the tapered part 25 of the sleeve 24, said rod 18 will be clamped sufficiently tight to prevent any further backward movement, although still permitting it to be rotated by the backward movement of the nut 15.

The exhaust from the cylinder is caused to be discharged through the drill for the purpose of blowing out the clay as it is cut by the drill.

The drill is provided with a suspension system which consists of a flexible cord or cable 38 attached thereto, which extends upwardly and over suitable guiding pulleys 39, and thence downwardly to a winding shaft 40 (see Fig. 2). The suspension system also comprises the two links 41 which are connected to the central portion of the drill casing at their lower ends, and at their upper ends are pivoted to a suitable bracket 42 secured to the bustle pipe 4.

43 designates a hook which is pivoted to the drill casing and which, when the drill is in operative position, as shown in full lines in Figure 1, is adapted to be engaged with the shaft 7^a of the dogs 7, thereby holding the drill in proper relation to the tapping hole 6.

45 After the tapping operation is completed, the cord or cable 38 is wound on the shaft 40, thereby swinging the drill upwardly until it assumes the suspended position shown in full lines in Figure 2 and in dotted lines in Figure 1. In this position, it is sufficiently elevated to be entirely out of the way of other operations around the base of the furnace.

55 My invention provides very simple and desirable apparatus for the purpose for which it is intended. It can be readily moved into position and set in operation, after which it continues to operate until the tapping hole is drilled out, without necessitating the presence of workmen in the immediate vicinity of the tapping hole. When the tapping out operation is finished, the device can be readily moved to its inoperative position, where it remains until it is again desired to use it.

I claim:

1. Blast furnace tapping apparatus comprising a rotatable drill, and suspension means therefor comprising a plurality of links pivotally connected at each end and arranged to permit the drill to be swung into substantially horizontal tapping position or into substantially vertical inoperative position, substantially as described. 70

2. Blast furnace tapping apparatus comprising a drill, and suspension means therefor arranged to permit the drill to be swung into and out of tapping position, said suspension means comprising spaced links pivoted at their lower ends to spaced points 80 on the drill and at their upper ends to spaced points on a bustle pipe, substantially as described. 75

3. Blast furnace tapping apparatus comprising a drill, and suspension means therefor arranged to permit the drill to be swung into and out of tapping position, said suspension means comprising links pivoted at their lower ends to the drill and at their upper ends to an overhead support, whereby 90 the drill may lie in substantially horizontal position below the support or in substantially vertical inoperative position at one side of the support, together with a flexible connection for raising and lowering the apparatus and for holding the drill suspended in its inoperative position, substantially as described. 95

4. Blast furnace tapping apparatus comprising a drill, spaced links forming a suspension for the drill and causing the same to move to an overhead position through a predetermined path, other suspending means for the drill, and spaced means for holding the drill temporarily in operative relationship to the tapping out hole of a blast furnace, substantially as described. 100

5. Drilling apparatus comprising a cylinder, a piston arranged to reciprocate in said cylinder, a sleeve to which the piston is secured, a nut carried by said sleeve, a spirally grooved rod engaging said nut and having a drill socket, and means controlled by said sleeve for automatically reversing the direction of travel of said piston, substantially as described. 110

6. Drilling apparatus comprising a cylinder, a piston arranged to reciprocate in said cylinder, a sleeve member to which the piston is secured, a nut carried by the sleeve member, and a spirally grooved rod engaging said nut and having a drill socket, together with means for directing the exhaust from said cylinder through said rod and drill socket, substantially as described. 120

7. Drilling apparatus comprising a cylinder, a piston arranged to reciprocate in said cylinder, a sleeve member to which the piston is secured, a nut carried by the sleeve member, and a spirally grooved rod engag- 125
130

ing said nut and having a drill socket, together with a conduit connected to the exhaust of the cylinder and leading through said rod and drill socket, substantially as described.

8. Drilling apparatus comprising a cylinder, a piston arranged to reciprocate in the cylinder, a sleeve member to which the piston is secured, a nut carried by the sleeve member, a spirally grooved rod engaging said nut and having a drill socket, and a clutch device for normally preventing the return movement of said rod upon the re-

turn stroke of the piston, substantially as described.

9. Blast furnace tapping apparatus, comprising a bustle pipe, suspension means pivotally connected at spaced points to said pipe, a drill pivotally connected to said suspension means, and means for swinging the drill into and out of operative position with the furnace, substantially as described.

In testimony whereof, I have hereunto set my hand.

EDGAR E. BROSIUS.
